CLAYTON HULSLANDER, OF ELMIRA, NEW YORK, ASSIGNOR TO DUPLEX VITALIZER MANUFACTURING CORPORATION, OF ELMIRA, NEW YORK, A CORPORATION OF NEW YORK.

AUTOMATIC AIR-VALVE FOR EXPLOSIVE-MOTORS.

1,202,067.

Specification of Letters Patent.

Patented Oct. 24, 1916.

Application filed April 12, 1916. Serial No. 90,659.

To all whom it may concern:

Be it known that I, CLAYTON HULSLANDER, a citizen of the United States of America, residing at Elmira, in the county of Chemung and State of New York, have invented certain new and useful Improvements in Automatic Air-Valves for Explosive-Motors, of which the following is a specification.

This invention relates to new and useful improvements in automatic air valves for explosive motors.

The primary object of the invention is the provision of a means for controlling the richness of the explosive mixture for an internal combustion motor whereby the same is automatically varied during the changing speeds of the motor.

A further object of the invention is the provision of an air intake valve for the explosive mixture forwardly of the carburetor, the position of such valve being automatically controlled by suction or partial vacuum created by connecting the valve chamber with a point adjacent an intake valve of the motor.

It is known that air valves have heretofore been employed controlled by a communication afforded with the motor exhaust as well as a control from a point in the carburetor outlet adjacent the position of an air inlet, and the same is not now broadly claimed; but it is believed to be new to provide an air inlet valve of the construction and operation herein set forth and which has a vacuum chamber communicating with the intake manifold at a point adjacent the motor and one of the intake valves thereof whereby a maximum vacuum for closing the valve will be created upon the starting of the motor and will be decreased for opening the valve during the increased speed thereof.

With these general objects in view and others that will appear as the nature of the invention is better understood, the same consists in the novel combination and arrangement of parts hereinafter fully described, illustrated in the accompanying drawing and then claimed.

In the drawing forming a part of this application and in which like designating characters refer to corresponding parts throughout the several views:—Figure 1 is a side elevation of a motor having the present device mounted upon the gasoline intake manifold thereof. Figs. 2, 3 and 4 are similar

central radial sectional views through the air valve illustrated respectively as normally closed at its outer seat when the motor is at rest, as closed upon its inner seat when the motor is first started and arranged in its open position during the usual running of the motor. Fig. 5 is a top plan view of the valve casing. Fig. 6 is a bottom plan view thereof, and Fig. 7 is a perspective view of the operating valve detached.

A motor 10 is herein illustrated provided with four cylinders 11 arranged *en bloc* and having an intake manifold 12 leading from the carburetor 13 to the upper portions of the said cylinders communicating directly with the latter by means of cross head portions 14 of the branches 15 of the manifold pipe, the upright 16 of which is attached to the carburetor after the usual manner of such motor connections.

An air intake valve for the manifold upright 16 is arranged in the form of a cylindrical casing 17 connected by means of a stub pipe 18 with the said upright at a point between the carburetor and the top of the upright 16 where the branches 15 spread outwardly from the upright. The partition 19 is arranged within the casing 17 at a point above the entrance opening 20 thereof arranged for the stub pipe 18 and is provided with an annular valve seat 21 upon its upper end surrounding a central opening in which the upper end of a tubular piston chamber or casing 22 is secured lying flush with the said valve seat.

The casing 17 is provided with a bottom 23 having a central opening corresponding in diameter and arranged in alignment with the opening of the partition 19, which bottom opening accommodates the piston casing 22 projecting outwardly and downwardly therethrough and having a cap 24 upon its lower end arranged with a central perforation 25 therein. The partition 19 is adapted to be forced inwardly of the casing 17 through the open bottom thereof and arranged with an annular notch or groove for seating upon an annular shoulder 26 internally of the casing 17, while the bottom 23 is retained in seating engagement with a similar shoulder 27 at the lower end of the casing 17 and whereby the piston casing 22 is secured axially of the valve casing 17 and is provided with air inlet ports 28 through its side wall at points between the bottom

23 and partition 19 and adjacent the said partition being arranged about the air outlet 20 of the said valve casing.

The valve casing 17 is provided with a top 29 having a central opening 30 for the entrance of air of substantially the same diameter as the piston casing 22 and provided with an inwardly arranged valve seat 31 positioned opposite to and parallel with the 10 aforementioned valve seat 21. A valve 32 of the form best illustrated in Fig. 7 of the drawing is shiftably arranged within the casing 17 having a stem 33 provided with a piston 34 at its inner end arranged for longitudinal movement within the piston casing 22 and having an air tight packing 35 carried by the said piston for making a tight engagement with the said piston casing. A valve disk 36 is carried by the outer end of 20 the stem 33 between the valve seats 21 and 31 being of greater diameter than the piston 34 and casing 22 and of substantially the same diameter as the said oppositely arranged valve seats which the disk 36 is 25 adapted to engage during the operation of the device.

A communicating pipe 37 is connected by means of a union 38 with the cap perforation 25 and by means of a nipple 39 with 30 one of the manifold cross heads 14 at a point adjacent an intake valve (not shown) of one of the motor cylinders 11. A helical spring 40 is arranged within the casing 22 being tensioned between the cap 24 and the adjacent end of the valve piston 34 whereby the valve disk 36 is normally maintained in seated engagement with the upper seat 31 of the valve casing 17.

When the motor is at rest, the valve will 40 be arranged closed as above noted in the position illustrated in Fig. 2 of the drawing. As the motor 10 is started in operation a vacuum is created within the piston chamber 22 beneath the piston, thereby lowering the piston and seating the valve 36 upon the partition seat 21 thus cutting off the admission of air. As the speed of the motor increases, the vacuum within the pipe 37 and beneath the piston 34 will be decreased allowing the spring 40 to slightly unseat the valve, as illustrated in Fig. 4 of the drawing and whereby the air will pass through the opening 30 around the valve disk 36 and into the casing 22, out through the ports 28 in the annular chamber 41 of the casing 17 between the said casing partition and bottom and thence through the stub pipe 18 into the manifold upright 16. The usual running position of the valve 32 for admitting the maximum amount of air to the manifold upright 16 is with the disk 36 positioned substantially centrally between the valve seats 21 and 31, while a decrease in the speed of the motor increases the vacuum 65 within the vacuum chamber 42 of the piston

casing 22 beneath the piston 34 and automatically draws the valve downwardly closing the disk 36 upon its seat 21.

Greater efficiency results from arranging the present point of communication between 70 the pipe 37 and intake manifold at a point as close as possible to the intake valve of one of the motor cylinders 11 instead of connecting the same at any points hereofore devised upon the intake or upon the exhaust. As above noted, when the motor 10 is running at low speed the degree of vacuum in the chamber 41 is greater than running at high speed, this being for the reason that the butterfly valve (not shown) of 80 the carburetor 13 is in a closed or partially closed position during the slow speed of the motor and by allowing little or no entrance of air, the suction of each piston of the motor is at its maximum and creates a maximum vacuum within the chamber 42. As the butterfly valve is opened to increase the speed of the motor it opens up a free entrance to the atmosphere decreasing the suction within the intake 12 and thus decreasing the vacuum within the valve chamber 42. 85 The spring 40 is arranged of the proper tension to maintain the valve closed upon its upper seat 31 when the motor is idle and also when the vacuum within the chamber 42 is reduced below a predetermined degree.

There is no communication between the chamber 42 and the air passages above the piston 34 and it will thus be seen that a simple device is arranged whereby the air inlet to the manifold upright is automatically controlled by an intake valve of the motor in a manner to insure the greatest efficiency of the motor by proper regulation or dilution of the explosive mixture after leaving the carburetor. 100

While the form of the invention herein shown and described is what is believed to be the preferable embodiment thereof, it is nevertheless to be understood that minor changes may be made in the form, proportion and details of construction without departing from the spirit and scope of the invention as hereinafter claimed. 110

What I claim as new is:—

1. A device of the class described comprising in combination with an intake manifold of an explosive motor, an air valve casing tapped into the said manifold and having an air passage therethrough, a controlling valve for said passage and a vacuum controlling means for the said valve communicating with the said intake pipe at a point adjacent one of the intake valves of the motor. 120

2. A device of the class described comprising in combination with a motor intake manifold, a valve casing, a partition within said casing having an opening therethrough, a stub pipe connecting the manifold with the 125

said casing at a point between the said partition and the casing bottom, a piston cylinder extending axially of the said casing through the said partition and bottom and 5 having air ports arranged between the said partition and bottom, a controlling valve within the said cylinder and operative connections between the said cylinder and intake.

10 3. A device of the class described comprising in combination with a motor intake manifold, a valve casing, a partition within said casing having an opening therethrough, a stub pipe connecting the manifold with the 15 said casing at a point between the said partition and the casing bottom, a piston cylinder extending axially of the said casing through the said partition and bottom and having air ports arranged between the said 20 partition and bottom, a valve having a piston at its inner end slidably arranged within the said cylinder and provided with a disk valve at its outer end adapted for seating upon the said cylinder, and means for automatically controlling the vacuum beneath 25 the said cylinder.

4. A device of the class described comprising in combination with a motor intake manifold, a valve casing, a partition within 30 said casing having an opening therethrough, a stub pipe connecting the manifold upright with the said casing at a point between the said partition and the casing bottom, a piston cylinder extending axially of the said 35 casing through the said partition and bottom and having air ports arranged between the said partition and bottom, a valve having a piston at its inner end slidably arranged within the said cylinder and provided with a disk valve at its outer end adapted for seating upon the said cylinder, and means for automatically controlling the vacuum beneath 40 the said cylinder.

5. A device of the class described comprising in combination with a motor intake 50

manifold, a valve casing, a partition within said casing having an opening therethrough, a stub pipe connecting the manifold with the said casing at a point between the said partition and the casing bottom, a piston 55 cylinder extending axially of the said casing through the said partition and bottom and having air ports arranged between the said partition and bottom, a valve having a piston at its inner end slidably arranged within 60 the said cylinder and provided with a disk valve at its outer end adapted for seating upon the said cylinder, a top upon the said casing having an air inlet opening therein and provided with a valve seat positioned 65 adjacent the said disk, the said cylinder ports being at all times between the said piston and disk, resilient closing means for the said valve, and pipe communications between the free end of said intake pipe and the said cylinder at a point beneath the said valve.

6. A device of the class described comprising in combination with a motor intake manifold, a valve casing, a partition within 75 said casing having an opening therethrough, a stub pipe connecting the manifold with the said casing at a point between the said partition and the casing bottom, a piston cylinder extending axially of the said casing through the said partition and bottom and having air ports arranged between the said partition and bottom, a valve having a piston at its inner end slidably arranged within the said cylinder and provided with 80 a disk valve at its opposite end adapted for seating upon the said cylinder, resilient closing means for the said valve, and pipe communications between the free end of said intake pipe and the said cylinder at a point 85 beneath the said valve.

7. An article of manufacture comprising an air valve casing having an air outlet, spaced valve seat members adjacent the said outlet, a valve disk for the said seats, a suction controlled piston carried by the said disk and automatically operated changing means for the said suction. 95

In testimony whereof I affix my signature.

CLAYTON HULSLANDER.
